US0D1094089S

(12) **United States Design Patent** (10) Patent No.: **US D1,094,089 S**
(45) Date of Patent: ** *Sep. 23, 2025

(54) **PACKAGE**

(71) Applicant: **The Procter & Gamble Company**,
Cincinnati, OH (US)

(72) Inventors: **William Michael Cannon**, West
Harrison, OH (US); **Richard**
Christopher Hagee, Cincinnati, OH
(US); **John Charles Van Rens**,
Cincinnati, OH (US)

(73) Assignee: **The Procter & Gamble Company**,
Cincinnati, OH (US)

(*) Notice: This patent is subject to a terminal disclaimer.

(**) Term: **15 Years**

(21) Appl. No.: **29/994,347**

(22) Filed: **Mar. 20, 2025**

CLAIM

The ornamental design for a package as shown and described.

DESCRIPTION

FIG. 1 is a perspective view of the package;
FIG. 2 is a front view of the package of FIG. 1;
FIG. 3 is a side view of the package of FIG. 1;
FIG. 4 is a rear view of the package of FIG. 1;
FIG. 5 is a side view of the package of FIG. 1 opposite the
side view of FIG. 3;
FIG. 6 is a top view of the package of FIG. 1; and,
FIG. 7 is a bottom view of the package of FIG. 1.
The broken lines in the drawings depict portions of the
package that form no part of the claimed design.

1 Claim, 4 Drawing Sheets
